UNITED STATES PATENT OFFICE.

C. S. HUNT, OF PARISH OF TERREBONNE, LOUISIANA.

IMPROVEMENT IN HEATING-DEVICE FOR CHAIRS, &c.

Specification forming part of Letters Patent No. 78,742, dated June 9, 1868.

To all whom it may concern:

Be it known that I, C. S. HUNT, of the parish of Terrebonne, and State of Louisiana, have invented a certain new, useful, and Improved Contrivance for Warming Purposes; and I do hereby declare the following to be a full, clear, and exact description of the same, reference being had to the annexed drawing, making a part of this specification.

My invention has for its object to provide a cheap and portable means of warming in and as to those places or situations in which a stove, fireplace, or other usual method of producing heat, cannot with safety or convenience be used; and it consists simply in heating the seat of a chair, stool, or other like thing, by the agency of a jet of burning-gas, conducted by a flexible tube underneath the same, or by some equivalent substitute for said jet. My invention is, in fact, founded upon the long-ascertained and settled physiological fact, that if the lower part of the human body, embracing, as it does, the lower end of the spinal column, be kept warm, the extremities, to wit, the feet and hands, can never become uncomfortably cold.

In order to make my invention available in the attainment of the end sought for, it is requisite to make the seat of the chair or stool, or other thing that is applied to analogous uses, whatever may be its name, of soapstone or some equivalent substance, or else, when the same is already in a finished state, or of ordinary construction, to introduce an inferior or lower plate or slab, of some material of strong radiating properties, just below the seat, so as to produce the same effect without bringing the lower part of the body of the person who sits upon it into actual contact with the object on which the burning gas directly acts. And in order, furthermore, to make the action of the flame of gas or its equivalent more pronounced and decided in its effects, I propose to use a reflector, in the form of a hollow inverted cone, within which, near the truncated apex of the same, the gas-jet is placed, to reflect the diverging rays of heat in an upward direction, and thus to bring them into contact with the seat or underlying plate, as the case may be, and so utilize the whole of the heat that is evolved from said jet or its substitute. I propose, furthermore, in adapting my in-

vention to the use of invalids or very aged persons, in whom the circulation of blood is inactive, to make the upright parts that constitute the supports of the back, as well as the arms of the chair, in such manner as that the heat will extend into them, in order to warm the backs and arms, as well as the lower parts of the bodies of such persons. In such form of construction, and, indeed, under many other conditions, it might be expedient to substitute for the inverted-cone reflector a pendent encircling screen or curtain, that need not in all cases be of metal, around the whole space covered by the seat of the chair, and extending to a greater or less distance below the flame of gas, or such substitute for it as may be employed. As applied to beds, lounges, or similar resting-places, my invention would be equally useful and beneficial to invalids, the very aged, or even to persons whose means are too limited to enable them to procure a sufficiency of fuel or bed-clothing to keep them comfortable during the long nights of the winter season.

There are still other adaptations and uses to which my invention may be readily applied, but those I have indicated are enough to demonstrate its immense value, alike as an economic and as a humanitarian instrumentalities.

My invention will be clearly understood by reference to the drawing, which is a representation of it in the form of an ordinary chair, at Figure 1, in perspective, and at Figure 2, in a transverse sectional view.

As shown upon the drawing, A represents the ordinary seat of a chair, which may be, we will suppose, of open-work cane, except around its edges, or of any other material whatsoever. Just below the seat A is the plate B, which we may suppose to be composed of soapstone, or of metal, or of any other substance possessing strong radiating properties, to which, as shown, is attached the inverted funnel-shaped reflector C. Within this reflector, at a point a little above the line at which the apex is cut off, as clearly shown at Fig. 2, the jet of gas or the substitute for it is placed or located. In order that a sufficient supply of air for supporting combustion inside the inverted conical reflector C may enter the said reflector, the apex of the same is cut off in such manner as that a considerable open space shall surround the

gas-pipe or lamp, as the case may be, as shown on the drawings, through which the air may freely pass, or, if this be not sufficient, minute perforations may be made at any suitable point in said reflector to subserve such purpose. It will be seen from this arrangement that the divergent rays of heat will strike upon the upward inclined surface of this reflector as they radiate from the burning gas, and be reflected against the plate B, to be by it absorbed for transmission to that part of the body of any person seated upon the seat A that is in contact therewith.

A simpler arrangement would be to apply the reflector directly to a seat, of soapstone or other equivalent substance, for in that case the plate B would not be required.

A mere glance at the drawing will indicate the *modus operandi* of my invention without special description, and also that it localizes the heat or warmth that is created by it in such manner as to confine it exclusively to the specific object of communication with that part of the body which, being warmed, warms the whole system.

I am well aware that footstools, such as Alonzo Palmer's patent corrugated sheet-metal foot-warmer, foot-stoves for travellers, and the like, are not new. I am also aware that heated blocks of soapstone and similar substances have long been used for keeping the feet warm for a certain space of time, but my invention is a fundamentally different thing, and I expressly disclaim these, as well as all similar contrivances; but having fully described my invention, and pointed out its peculiar characteristics,

What I do claim, and desire to secure by Letters Patent, is—

A chair, constructed substantially as herein described, that is to say, provided with the metal bottom, and the combustion-chamber, adapted to receive a gas-jet or its equivalent, substantially as and for the purpose described.

C. S. HUNT.
